WEIGHING SCALE

Homer Butler, Bronaugh, Mo.

Application August 10, 1933, Serial No. 684,598

4 Claims. (Cl. 265—68)

This invention relates to improvements in signal devices and pertains particularly to a signal device designed for use in association with a dispensing apparatus.

5 The primary object of the present invention is to provide a device designed for application to a dispensing faucet, upon which a receiving receptacle may be suspended and which will indicate by an unmistakable signal when a predetermined quantity of fluid has passed into the receptacle.

10 Another object of the invention is to provide a signal device of the above described character which is of simple design, easily attached to or detached from a dispensing faucet, and requiring little attention to keep in order.

15 The invention will be best understood from a consideration of the following detailed description taken in connection with the accompanying drawing forming part of this specification, with the understanding, however, that the invention is not confined to any strict conformity with the showing of the drawing but may be changed or modified so long as such changes or modifications 20 mark no material departure from the salient features of the invention as expressed in the appended claims.

In the drawing:—

25 Figure 1 is a view illustrating the application 30 of the device embodying the present invention to a dispensing faucet and showing, in broken lines, a receptacle suspended therefrom;

35 Figure 2 is a view of the interior of the device looking at the same from the rear, portions being in section;

40 Figure 3 is a vertical sectional view taken substantially upon the line 3—3 of Figure 2;

45 Figure 4 is a sectional view taken substantially upon the line 4—4 of Figure 3.

50 Referring now more particularly to the drawing wherein like numerals of reference indicate corresponding parts throughout the several views, the numeral 1 indicates a faucet of the type commonly employed on tank wagons in which gasoline, oil or other liquids are transported. From these wagons the liquid is drawn off through the faucet into receptacles of different capacities, for sale.

55 The device embodying the present invention is designed to be attached to the pipe 2 with which the faucet 1 is connected and is indicated as a whole by the numeral 3.

The device 3 comprises a casing 4 having a transparent front panel 5 and a removable back wall 6. Connected with the casing is a clamp of

a suitable character, such for example as the split ring clamp 7, the ends of which are drawn together by a connecting bolt 8, by means of which the device is attached to the pipe 2 to be suspended therefrom.

5 Within the casing 4 is mounted, in spaced relation with the transparent panel 5, the dial 9, the outer face of which is viewable through the glass panel 5 and bears an annular series of notations which in the present case are illustrated as running by fives from zero to one hundred. These notations in the present instance represent gallons of liquid.

10 Extending through the radial center of the dial 9 and through the back 6 and passing through the casing 4, is a shaft 10 upon the forward end 15 of which is a signal indicator hand 11 which rotates over the face of the dial behind the glass panel 5.

15 Upon the opposite side of the casing and the other end of the shaft 10, is a key 12 by means of which the shaft may be rotated when and as necessary.

20 Within the casing 4 there is secured the body 13 against the back of the dial 9 and the shaft 25 10 passes through the center of this body. Pivotally mounted upon the body 13 at the point 14 is a pawl 15 which is integral with the elongated tail-piece 16 which terminates in an angularly extending arm 17. Upon this arm 17 is 30 fixed a hammer 18.

25 Mounted upon the back of the dial 9 is a bell 19 adjacent which the hammer 18 is disposed and with which the hammer comes in contact during the operation of the device to give the desired signals.

30 A pin 20 mounted upon the back of the dial 9 has secured thereto one end of a flat spring 21 which intermediate its ends extends across and is in contact with a stop pin 22. Connected 40 with the free end of the spring 21 is a link 23 through which the tail-piece 16 of the pawl passes.

35 Mounted upon the shaft 10 for free rotation therewith, is a drum 24 having a flange 25 in which are formed the teeth 26. Upon the back of the drum 24 is a ratchet 27 with the teeth of which the pawl 15 engages.

40 The shaft 10 extends through one end of a lever arm 28 and the arm rocks freely on this 50 shaft. This arm 28 passes across the toothed edge 26 of the drum 24 and extends through an aperture 29 in the wall of the casing 4, terminating at its outer end, exteriorly of the casing 4, in the hook 30. The lower edge of this ap- 55

erture 29 limits the downward movement of the arm 28 and as the arm is swung down its lower edge, which is in contact with a tooth 26, causes a partial rotation of the drum 24 upon the shaft. The lever arm 28 is of suitable flexibility to permit it to bend slightly laterally to pass over the teeth 26 in its reverse movement on the shaft. Suitable means is employed for retaining the arm 28 in its proper position on the shaft, such for example, as the collar 31. This retains the inner end of the arm in place.

Extending through a boss 32 upon the outside of the wall of the casing is a threaded stem 33 with which is engaged a nut 34 which rests upon the boss. The inner end of this stem is bifurcated and each of the furcations is formed to provide a hook 35. Surrounding the bifurcated portion of the stem 33 is a coil spring 36, the lower end of which rests against the hooks 35. The upper end of the spring 36 is connected with a link 37 which passes downwardly therethrough and has engagement with the arm 28 as is clearly shown in Figures 2 and 4. By the adjustment of the nut 34 upon the stem 33 the tension of the spring can be increased or decreased as it will tend to pull the arm upward while its movement is limited by the upper edge of the aperture 29.

In the operation of the present device after the same has been attached to a faucet pipe as illustrated in Figure 1 and the nut 34 adjusted to properly tension the spring 36, when a receptacle, such as is indicated at 38, is suspended from the hook 31 it will be disposed beneath the faucet 1 to receive fluid therefrom and when the faucet 3 is opened and an amount of fluid equal to five gallons has flowed into the receptacle, the arm 28 will have been pulled down to the point where, through its contact with one of the teeth 26, the drum 24 will have been rotated sufficiently to cause a tooth of the ratchet 27 to pass the point of the pawl 15. As the tooth of the ratchet 27 is riding under the point of the pawl 15 the tail portion 16 of the pawl will be swung so as to flex the spring 21 and when the pawl snaps off of the tooth the hammer 18 will be caused to snap back against the bell, thus signalling to the attendant that the receptacle 38 contains a pre-determined amount of the liquid.

It is, of course, to be understood that various adjustments of the tension of the spring 36 must be made to accord with the specific gravity of the liquid being handled and after an adjustment has once been made so that the weight of five gallons of the liquid to be measured will be just sufficient to pull the arm 28 down, after making due allowance for the weight of the receptacle used, then the device may be used continuously for the same fluid and with the same receptacle to measure off the fluid in five gallon quantities and to record these measurements up to one hundred gallons or any other quantity for which the device may be set.

While the style and arrangement of the clamp 7 and hook 30 is preferred as illustrated, it is to be understood that the arrangement of these elements may be made to suit the convenience of the user and the invention is not to be restricted to the particular form and arrangement illustrated.

Having thus described the invention, what is claimed is:—

1. A device of the character described, comprising a housing, a shaft rotatably mounted in the housing, a lever mounted at one end on said shaft for free oscillation thereabout, a drum mounted concentrically on and secured to the

shaft for rotation therewith and having ratchet teeth with which said lever contacts, means securing the lever against longitudinal movement on the shaft, means preventing rotation of the drum and shaft in one direction only, means normally resiliently holding the lever in one position, said lever when oscillated on the shaft away from said position engaging one of said teeth to rotate said drum, the lever being of sufficient flexibility to permit its passage over said teeth when reversely operated by the resilient means, an indicator which is operated with each movement of said lever in opposition to the resilient influence thereon, and means coupling the indicator with the shaft by which it is operated.

2. A device of the character described, comprising a housing having an aperture in a side wall thereof, a shaft extending through said housing and mounted for free rotation, a dial at one side of the housing, an indicator hand carried by said shaft at one end and overlying the dial, a drum having said shaft extending through the center thereof and secured to the shaft for rotation therewith, said drum having a flange concentric with the shaft in the edge of which ratchet teeth are formed, a ratchet formed upon the back of the drum concentric with the shaft, a pawl oscillatably mounted on the housing and engaging said last ratchet to permit rotation of the drum and shaft in one direction only, an elongated lever mounted at one end upon the shaft for oscillation independently of the same, said lever extending laterally through the wall aperture of the casing and terminating at its other end in a hook, means on the shaft for preventing the lever from moving longitudinally of the shaft, and resilient means engaging the lever and normally tending to swing the same upwardly, said lever when moved downwardly against said resilient means engaging a tooth of the drum flange to rotate the drum and shaft, said lever being of a flexible character to permit of its passage over the ratchet teeth of said drum when the same is swung upwardly by the said resilient means.

3. A device of the character described, comprising a housing having an aperture in a wall thereof, a shaft rotatably mounted in said housing, a drum secured concentrically to said shaft to rotate therewith and including a flange having ratchet teeth in the edge thereof, a ratchet body integral with the drum and concentric with the shaft, a pawl oscillatably mounted upon a fixed part of the housing and engaging the second ratchet, said pawl including an elongated arm, a signal element, means operating with each movement of said pawl over its ratchet teeth for the operation of said signal, an elongated lever having one end mounted upon said shaft for oscillation independently of the same and having its other end extended through said casing wall aperture and terminating in a hook, means upon said shaft for maintaining said lever against movement longitudinally of the shaft, and resilient means in the casing normally drawing said lever upwardly, the downward movement of the lever against said resilient means engaging a tooth of said drum to rotate the latter and the shaft, said lever being of a flexible character to permit of its passage over the ratchet teeth of said drum when the same is swung upwardly by the said resilient means.

4. A device of the character described, comprising a housing, a shaft rotatably mounted in the housing, a lever mounted at one end on said

shaft for free oscillation thereabout, a drum mounted concentrically on and secured to the shaft for rotation therewith and having ratchet teeth with which said lever contacts, means securing the lever against longitudinal movement on the shaft, means preventing rotation of the drum and shaft in one direction only, means normally resiliently holding the lever in one position, said lever when oscillated on the shaft away from

said position engaging one of said teeth to rotate said drum, the lever being of sufficient flexibility to permit its passage over said teeth when reversely operated by the resilient means, a dial forming one wall of the housing and having said shaft extending centrally therethrough, and a pointer secured at one end to the shaft and overlying said dial.
